(57) **CLAIM**

The ornamental design for pair of boots, as shown and described.

DESCRIPTION

FIG. 1 is a front perspective view of one left boot of a pair of boots, the left boot having a pendant ornament (in each instance, a right boot is implicitly included, the right boot being a mirror image of the left boot);

FIG. 2 is a front view thereof;

FIG. 3 is a back view thereof;

FIG. 4 is a left view thereof; and,

FIG. 5 is a bottom view thereof.

The broken lines in the drawings represent portions of the shoe that form no part of the claim.
